[57] CLAIM

The ornamental design for a trunk lid fastening holder, as shown and described.

DESCRIPTION

FIG. 1 is a top plan view of a trunk lid fastening holder embodying my design;

FIG. 2 is a front elevational view thereof, the rear being a mirror image;

FIG. 3 is a left end view of the device, the right end view being substantially the same; and,

FIG. 4 is a bottom plan view thereof.
